Attorney

UNITED STATES PATENT OFFICE

McWHORTER BEERS, OF LAUREL, MISSISSIPPI

LEDGER SHEET

Application filed June 7, 1930. Serial No. 459,734.

This invention relates to a ledger sheet, and it is an object of the invention to provide in connection with a sheet of this kind a signature card in direct association with the sheet in a manner whereby the original signature of a depositor is always in sight at the time the general ledger is being posted.

It is also an object of the invention to provide a sheet of this kind whereby a signature card may be properly positioned or arranged with respect to either face of the sheet.

The novel features of my invention will hereinafter be definitely claimed.

In order that my invention may be the better understood, I will now proceed to describe the same with reference to the accompanying drawing, wherein:—

Figure 1 is a fragmentary view in plan of a ledger sheet constructed in accordance with an embodiment of my invention;

Figure 2 is an edge view of the sheet as illustrated in Figure 1;

Figure 3 is a plan view of the signature card unapplied.

As disclosed in the accompanying drawing, S denotes a ledger sheet such as is employed in a bank and which sheet is provided, preferably in a marginal portion thereof, with two series of spaced slits 1, 1^b and 1^c, the slits 1, 1^b and 1^c in each series being herein disclosed in relatively close proximity. The slits 1 of both series are substantially in parallelism and at a point substantially midway the two series of slits, the sheet S is provided with a single slit 2 substantially at right angles to the slits 1 and arranged slightly beyond the field between the two series of slits 1.

The signature card A may be of any desired material or stock and upon this card a depositor applies his signature, as at 3. Each end portion of the card A is provided with an extending tongue 4 which is adapted to be threaded through the slits 1, 1^b and 1^c of one series. The tongue 4, immediately adjacent its juncture with the body proper of the card A at opposite sides thereof, is provided with the slits or notches 5 which are adapted to receive the portion of the

sheet S immediately adjacent the ends of the innermost slit 1 of a series whereby the applied card A is further effectively held in desired placement upon the sheet S.

The card A midway its ends also has extending from a margin thereof a tongue 6 which is insertible through the slit 2, thus providing additional means for maintaining the signature card in position upon the sheet.

While in the present embodiment of my invention I show the slits 1 and 2 arranged to position the applied signature card A to the left of the name and address of the depositor, I do not wish to be understood as limiting myself in this respect as these slits 1 and 2 may be placed at any location preferred upon the sheet.

It is believed to be obvious that in use after one side of the sheet has been filled or used the card A may be readily applied in position with respect to the opposite face of the sheet. It is also believed to be clearly apparent that the same card A may from time to time and as required be applied to different sheets.

My improved sheet and associated signature card are of especial advantage for use in banks and provide means whereby an original signature of a depositor may be carried by a ledger sheet with resultant manifest advantages and particularly to provide means whereby the original signature of a depositor is always in sight at the time the clerk is posting the general ledger.

I claim:—

1. As a new article of manufacture, a signature card adapted to be mounted on a ledger sheet having spaced parallel slits, comprising an elongated body, securing tongues carried by the body and engageable in said slits in the ledger sheet, and laterally extending locking means carried by the inner ends of said tongues and adapted to extend beyond the ends of said slits, whereby to hold said tongues against ready withdrawal from said slits, the end of the body and the confronting edge of the locking means forming an acute angle, the apex of which engages the adjacent end of a slit.

2. In combination with a ledger sheet having a plurality of spaced slits therethrough a signature card of a width in excess of the length of the slits and having outstanding tongues on the ends thereof adapted to be threaded into said slits, laterally extending locking means carried by the inner ends of said tongues and adapted to extend beyond the ends of said slits, said locking means cooperating with the adjacent end of the card to hold the card and the tongue against movement relative to the slit.

In testimony whereof I hereunto affix my signature.
